CLAIM

The ornamental design for a razor package, as shown and described.

DESCRIPTION

FIG. 1 is a front perspective view of a razor package showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a second front perspective view thereof; and,

FIG. 9 is a perspective environmental view thereof.

The dash lines shown illustrate portions of the package and form no part of the claimed design. The dash-dot-dash lines represent unclaimed boundary lines between the claimed and unclaimed subject matter.
